(57) **CLAIM**

The ornamental design for a container for packaging, as shown and described.

DESCRIPTION

FIG. 1 is a perspective view of a container for packaging, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a partial enlarged view of an area labeled 8 in FIG. 1.

The dash-dash broken lines in the drawings show portions of the container for packaging that form no part of the claimed design. The dot-dash broken lines depict boundaries of the claimed design and form no part thereof.
